UNITED STATES PATENT OFFICE

2,300,209

RECORD REPRODUCING DEVICE

Donald R. De Tar, Stratford, Conn., assignor to
 General Electric Company, a corporation of
 New York

Application March 6, 1941, Serial No. 381,933

6 Claims. (Cl. 192—124)

My invention relates to record reproducing devices and it has for one of its objects to provide an improved and simplified mechanism for controlling the operation of the playing mechanism of such a device in response to movement of the pick-up arm thereof.

In record playing devices of the disc record and turn table type, an arm carrying the pick-up device and stylus is generally pivoted beyond the periphery of the turn table to swing over the turn table during the playing of the record. It is often desirable to provide means to control the motor which is utilized to drive the turn table in response to movement of this pick-up arm. For example, it may be desirable to energize the 15 motor in response to extreme outward movement of the pick-up arm, to deenergize it in response to extreme inward movement of the pick-up arm, or to deenergize it in response to reversal of its movement during the playing of a record or when its stylus enters the usual eccentric groove at the end of the record. In this way the motor is very conveniently and satisfactorily controlled wholly in response to movement of the tone arm, both manually, and by certain movements occurring by operation of the record itself.

An object of my invention is to provide improved and simplified means for effecting such control.

A further object of my invention is to provide such means comprising simple stamped out metal parts which may be assembled as a unit about the pivot of the pick-up arm and which operates to effect the desired control entirely in response to movement of that pivot.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 represents an embodiment of my invention, and Figs. 2 and 3 represent the invention in different conditions of its operation.

Referring to the drawing, and particularly to Fig. 1 thereof, I have indicated at 1 therein the turn table of a phonograph having a disc record 2 lying thereon, said record having the usual groove indicated by the shaded portions 3 of the record, which groove is indicated as terminating in an eccentric groove 4 at the center of the record.

The turn table is driven by a motor 5, located beneath the turn table, through pinions indicated by dotted lines at 6 and 7, the latter pinion being arranged to engage the inner surface of the 5 downward flange at the outer periphery of the turn table in a manner quite customary in phonographs of today.

The energizing circuit of the motor is indicated at 8 as including a switch comprising a pair of stationary contacts 9 arranged to be engaged by a movable contact 10 carried on an armature 11 controlled through means provided in accordance with my invention and which will presently be described.

Over the turn table is shown a pick-up arm 12 carrying a stylus 13 which engages with the record. This pick-up arm is pivoted for movement in the vertical plane about a pivot 13 and for movement in the horizontal plane about a 20 pivot 14. The pivot 14 comprises a vertical shaft which may extend downward into the housing of the mechanism, which housing is not shown on the drawing. At the lower portion thereof, preferably within the housing, a ratchet member 15 is attached to the shaft 14 for movement therewith. This ratchet member thus moves in a clockwise direction during the playing of the record and in a counterclockwise direction as the pick-up arm is moved toward its outer position. It of course 25 oscillates when the stylus of the pick-up arm rides in the eccentric curve at the end of the record.

About the ratchet 15 are two additional levers 16 and 17 lying substantially in the same plane 30 as the ratchet 15 and which are pivoted about points 18 and 19 respectively. These levers 16 and 17 extend from their pivots toward each other, and abut against each other, as shown at 20, each lever being biased by its respective 35 spring 21 and 22 for movement toward the other.

Each of these levers is provided with an additional arm 23 and 24 made integral therewith whereby they may be actuated in response to the 40 extreme movements of the pick-up arm. Upon 45 extreme inward movement of the pick-up arm the arm 24 of lever 17 is engaged by an ear 25 on the ratchet 15 so that it is actuated counterclockwise about its pivot against the bias of spring 22, thereby releasing lever 16 for movement under 50 its bias.

Arm 23 of lever 16 is likewise arranged to be 55 engaged upon extreme outward movement of the pick-up arm by an ear 26 on the ratchet 15 thereby to move the lever 16 against its bias. This in turn releases lever 17 for movement under

influence of its bias spring 22 back to the position shown in Fig. 1. In this way the device is reset.

The movements of the lever 16 are utilized to control the switch 9, 10 in the manner which I shall now indicate. The armature 11 carries a pivot 27 to which is attached a member 28 having two prongs 29 which straddle a projection 30 on the lever 16. This member 28 is attached to the member 11 through a coiled spring 31 at such a point that when lever 16 is in the position shown this spring biases armature 11 to the closed position of the switch 9, 10. If lever 16 be moved to the right as by actuation of lever 17 in a counterclockwise direction by ear 25, then member 28 will be moved clockwise about the pivot 27 thus tensioning spring 31 and moving the point of connection of member 28 with spring 31 over center to such a position that this spring 31 now biases the armature 11 to an open position of the switch 9, 10. Thus, in this way the switch 9, 10 is operated from its open position to its closed position and vice versa in response to the reciprocations of the lever 16.

As thus described, the switch may be opened or closed in response to the extreme movements of the pick-up. Means are also employed for operating the switch in response to any reversal of the movement of the pick-up arm which occurs at any time during the playing of the record or when the stylus 13 enters the eccentric curve at the end of the record. This means comprises a pawl 33 which is pivoted at 34 upon the lever 17. The end of this pawl 33 opposite the pivot 34 is down-turned at 35 and this down-turned end is connected by a spring 36 to the pivot 19, the relative positions of the pivots 19 and 34 and the down-turned end 35 being such that the spring 36 biases the pawl 33 against the edge 37 of the ratchet 15. This edge may be provided with teeth inclined to permit movement of the ratchet 15 in the clockwise direction as during the playing of the record with the pawl 33 riding freely over the pivot, but shaped to engage the pawl 33 upon reversal of movement of the pick-up arm and thereby to transmit the movement of the ratchet 15 through the pawl to the pivot 34 and lever 17, thus moving that lever about pivot 19 in a counterclockwise direction against spring 22. The left end of lever 17 then moves out from the notch indicated at the point 20 and thus releases lever 16 to move under the bias of spring 31 until the edge 38 of the extension 30 of lever 16 engages the end of the lever 17. This counterclockwise movement of lever 16 operates the member 28 of the switch in a clockwise direction throwing spring 31 over center so that it then biases member 11 to the open position of the switch 9, 10.

The switch is then in the position which is illustrated in Fig. 2. It will be seen from Fig. 2 that the stylus which is carried by the pick-up arm 12 is in an eccentric groove 4 on the record in which it oscillates in accordance with the eccentricity of the groove as the record rotates. Pawl 33 has been actuated by the ratchet 15 to transmit its movement to the lever 17 which moved out from its notch 20 thereby releasing lever 16 for counterclockwise movement under its bias to the position illustrated. Member 28 of the switch is shown in its clockwise position in which the spring 31 biases member 11 to the open position of switch 9, 10.

Of course, this opening of the switch 9, 10 de-energizes the motor and stops the phonograph.

If it now be desired to start the phonograph,

the operator may grasp the pick-up arm and reset the device by rotating the pick-up arm to its extreme outer position. As he does this the ear 26 on the ratchet member 15, as illustrated in Fig. 3, engages the arm 23 of lever 16 and rotates that lever in a clockwise direction thus releasing lever 17 for movement under its bias spring 22 in the clockwise direction to the position shown in Figs. 1 and 3. Spring 36 and pawl 33 are now in such position that when the pick-up arm is placed over the record the pawl 33 again engages the toothed edge 37 of the ratchet member 15.

Now if at any time during the playing of the record the operator desires to stop the phonograph, he needs only to pick up the pick-up arm and move it outward. The first movement outward causes the pawl 33 to transmit the movement of ratchet 15 to the lever 16 and thus trip the mechanism from the position shown in Figs. 1 and 3 to the position shown in Fig. 2 and thus the switch is opened deenergizing the motor.

As thus described it will be seen that my invention is extremely simple comprising but a few stamped parts which may be readily assembled upon any suitable stationary bracket in the housing of the reproducing device. Moreover, it operates to effect its intended functions particularly efficaciously. The response to backward movement of the pick-up arm may be very sensitive if desired. In fact with pawl 33 properly proportioned and pivots 34 and 19 properly positioned, the teeth 37 may comprise little more than a roughened or finely serrated edge 35 of the ratchet plate.

While I have shown a particular embodiment of my invention it will, of course, be understood that I do not wish to be limited thereto since many modifications may be made in the structure and instrumentalities of which my invention may be formed and I contemplate by the appended claims to cover any such modifications as fall within the true spirit and scope of my invention.

What I claim as new and desire to secure by Letters Patent of the United States is:

1. The combination, in a record reproducing mechanism, of a ratchet movable about a pivot as a record is being reproduced, a lever extending from its pivot along said ratchet and having a pawl pivoted thereon, means to bias said pawl to ride over said ratchet during said movement of the ratchet and to transmit reverse movement of the ratchet to said lever to rotate said lever about its pivot, and a trip means responsive to said movement of said lever to control said record reproducing mechanism.

2. The combination, in a record reproducing mechanism, of a ratchet movable about a pivot as a record is being reproduced, a lever extending from its pivot along said ratchet and having a pawl pivoted thereon, means to bias said pawl to ride over said ratchet during said movement of the ratchet and to transmit reverse movement of the ratchet to said lever to rotate said lever about its pivot, a trip means responsive to said movement of said lever to control said record reproducing mechanism, and means responsive to extreme movement of said ratchet in the direction of said reverse movement to restore said lever and pawl and responsive to extreme movement of said ratchet in the direction of its forward movement to operate said trip means.

3. The combination, in a record reproducing mechanism, of a pair of levers pivoted at points

and extending therefrom to abut against each other at another point, each lever being biased to abut against the other and each lever restraining the other against further movement under its bias, a pick-up arm for said reproducing mechanism movable during reproduction of a record, a ratchet movable with said pick-up arm, a pawl pivoted on one of said levers and biased to ride over said ratchet during movement of said ratchet and to transmit reverse movement of said ratchet to said lever thereby to release the other of said pair of levers for further movement under its bias, and means to stop said mechanism in response to said further movement of said other lever.

4. The combination, in a record reproducing mechanism, of a pair of levers pivoted at points and extending therefrom to abut against each other at another point, each lever being biased to abut against the other and each lever restraining the other against further movement under its bias, a pick-up arm for said reproducing mechanism movable during reproduction of a record, a ratchet movable with said pick-up arm, a pawl pivoted on one of said levers and biased to ride over said ratchet during movement of said ratchet and to transmit reverse movement of said ratchet to said lever thereby to release the other of said pair of levers for further movement under its bias, means to stop said mechanism in response to said further movement of said other lever, and means responsive to extreme movement of said ratchet in one direction to actuate said one lever to release the other for said further movement under its bias.

5. The combination, in a record player, of a turn table, a motor to drive said table, a pick-up arm having a pivot near said table and arranged to swing inward over said table during the playing of a record and to rotate said pivot, a pair of levers having pivots near said first mentioned pivot and extending therefrom to abut

against each other in either of two positions, said levers being biased to abut against each other in said positions, each lever restraining the other against movement under its bias in either position and each lever being arranged when moved against its bias in its respective position to release the other for movement under its bias to the other position, and means responsive to extreme movement of the said pick-up arm in either direction to actuate the corresponding lever against its bias, a switch for controlling said motor, and means to operate said switch in accordance with the reciprocations of one of said levers.

15 6. The combination, in a record player, of a turn table, a motor to drive said table, a pick-up arm having a pivot near said table and arranged to swing inward over said table during the playing of a record and to rotate said pivot, a pair 20 of levers having pivots near said first mentioned pivot and extending therefrom to abut against each other in either of two positions, said levers being biased to abut against each other in said positions, each lever restraining the other against movement under its bias in either position and each lever being arranged when moved against its bias from a respective one of said positions to release the other for movement under its bias to the other position, means responsive to extreme movement of the said pick-up arm in either direction to actuate the corresponding lever against its bias thereby providing reciprocation of said levers between said positions, a switch for controlling said motor, means 25 to operate said switch in accordance with the reciprocations of one of said levers, and means responsive to reversal in the direction of movement of said pick-up arm during the playing of a record to actuate that one of said levers against 30 said bias which opens said switch.

DONALD R. DE TAR.
